TELEVISION APPARATUS

Rolf Möller and Georg Schubert, Berlin, Germany, assignors to Fernseh Aktien-Gesellschaft, Zehlendorf, near Berlin, Germany

Application September 7, 1932, Serial No. 632,038
In Germany September 12, 1931

6 Claims. (Cl. 178—6)

This invention relates to television apparatus, and more particularly to an arrangement for the operation of light sources, which make use of a positive column, in conjunction with television receiving apparatus of the type employing a Nipkow disk.

In the case of a relatively large number of image points it is impossible, owing to the poor density of light, to employ the ordinary gaseous conduction lamp hitherto usual in connection with receivers of the kind referred to, and in place thereof it is necessary to make use of brighter sources of light. Gas discharge tubes operating with a positive column have been found 15 to be the most suitable for this purpose.

In receiving apparatus of the type employing a Nipkow disk it is extremely important to place the source of light, for example the gaseous conduction lamp, as closely as possible behind the rotating disk. This does not present any difficulties 20 in connection with gaseous conduction lamps as hitherto employed, because the cathode surface thereof is equally bright at all points. On the other hand in the case of discharge lamps operating with a positive column an even intensity of 25 the image surface can only be obtained with the assistance of means causing a sufficient dispersion, for instance by the interposition of a piece of milk glass, as the surface in question requires 30 to be illuminated with a luminous tube, which is bent, for example, in meandrian form.

Surface illuminating means operating with a positive column (by this is meant a suitably bent luminous tube having a sheet of milk glass situated in front of the same) cannot, however, readily be employed for television purposes, as strata of light are formed in the luminous column of gas, or in other words the luminous column of gas readily tends to oscillate at a certain frequency. 35 These disturbances can only be avoided if the temperature of the light source does not sink below a certain value. In accordance, therefore, with the nature of the light source employed, a certain temperature requires to be ensured by 40 a way of external heating or, if the temperature is produced by the source of light itself, by a certain heat-insulating means. This is particularly important when using sodium light sources.

It is well known that sodium light sources require to be heated externally during their operation for the purpose of continuously maintaining a certain quantity of sodium in vaporous form.

It has been found by experiment that particularly in the case of sodium lamps it is extremely important to maintain a certain minimum tem-

perature. Sodium light sources, therefore, have been fitted in a good heat-insulated casing which, for the reasons set forth in the above, has been covered at the front with a sheet of milk glass. As already stated, this casing, or in other words 60 the milk glass, requires to be approached as far as possible towards the rotating Nipkow disk. The current of air produced by the rotating disk greatly cools the sheet of glass, and there occur on the one hand the disturbances above referred to arising from the oscillation, while on the other hand exactly the front portion of the light source becomes clouded, so that great losses of light occur, or operations are rendered entirely impossible.

Now it is the object of the invention to overcome the difficulties referred to, and this is accomplished by the method and means as described and ascertained in the following with reference to the accompanying drawing.

Fig. 1 illustrates in diagrammatical form the method hitherto adopted for approaching the gaseous conduction lamp or surface illuminating means towards the Nipkow disk.

Fig. 2 showing in similar form a possible arrangement according to the invention.

In Fig. 1 there are shown the Nipkow disk 1, the mask or shutter 2, and the surface illuminating means or gaseous conduction lamp 3.

In Fig. 2 there are shown the Nipkow disk 1, the surface illuminating means, i. e., the source of light, and its heating chamber 2, and a wall or partition 3, which is interposed between the light source and the Nipkow disk. This wall may consist of any desired material, and serves to 85 withhold the current of air created by the disk from the heating chamber or casing in which the light source is located. In place of the gate or image aperture there requires to be fitted in the wall 3 a piece of glass or other transparent material 4. In this manner it is accomplished that a one-sided cooling of the light source or surface illuminating means by reason of the current of air produced by the rotating disk is avoided. Certainly this arrangement is unable to prevent the loss of heat by radiation as regards the heating chamber, and accordingly the source of light, from being greater on the side directed towards the glass than at the remaining points, as it is not possible to provide heat-insulating means at the point where the milk glass is situated.

In order to prevent this irregular radiation of the heat the surface illuminating means are, in accordance with the invention, more greatly

heated on the front side than at the remaining points, which are well protected against radiation of the heat, by particular location of the heating elements within the chamber or casing.

5 Thus, for example, the arrangement of the heating elements within the chamber or casing may be in the form as illustrated diagrammatically in Fig. 3.

In the latter 1 is the chamber or casing, 2 the 10 heating elements, and 3 the light source fitted in the casing. As shown by the drawing, it is ensured by reason of the arrangement of the heating elements that exactly the front face 4 is continuously washed by heated air.

15 It will be understood that no restriction is made to the specific form of embodiment illustrated in the drawing, which has been quoted solely by way of example, and that various modifications are quite possible within the meaning of the above 20 description and the annexed claims without departing from the spirit of the invention.

What we claim as new and desire to secure by Letters Patent is:

25 1. In a television apparatus, a scanning disc, a luminous tube of the positive column type, a casing in which said luminous tube is mounted, said casing being provided with an aperture for the emission of light rays from said luminous tube, means adapted to keep the air current produced 30 by the rotation of said scanning disc away from said casing and luminous tube, said means including a frosted glass plate in front of said luminous tube, the space between the luminous tube and scanning disc being free of any other equipment, 35 and means for compensating the loss of heat caused by said air current.

2. In a television apparatus, a scanning disc, a luminous tube of the positive column type, a casing having an apertured wall in which said 40 luminous tube is mounted directly behind said wall, a partition between said scanning disc and the apertured wall of said casing, a window of heat resisting material in said partition, said partition being adapted to keep air currents produced by the rotation of said scanning disc away from said casing, and means for compensating the loss of heat caused by said air currents.

3. In a television apparatus, a scanning disc, a luminous tube of the positive column type, a casing having an apertured wall in which said luminous tube is mounted directly behind said wall, means for keeping air currents produced by the rotation of said scanning disc away from said casing and said luminous tube, and a heating element mounted in said casing and below the front side of said luminous tube.

4. In a television apparatus, a scanning disc, a luminous tube of the positive column type, a casing in which said luminous tube is mounted, means between said casing and said scanning disc for keeping air currents produced by the rotation of said scanning disc away from said casing and said luminous tube, and heating elements arranged in said casing in such manner as to compensate the loss of heat caused by said air currents.

5. In a television apparatus, the combination of a scanning disc with a luminous tube of the positive column type, a casing having an apertured wall in which said luminous tube is mounted directly behind said wall, a partition between said scanning disc and directly in front of the apertured wall of said casing, said partition covering the entire one side of the scanning disc and being provided in front of said apertured wall with a window plate of heat resisting material, and heating elements within said casing and located adjacent the front of said luminous tube.

6. In a television apparatus, the combination of a scanning disc with a luminous tube of the positive column type, a stationary partition directly adjacent one side of said scanning disc and covering the entire surface of the same, said partition being provided with an opening, said luminous tube being arranged directly behind the opening in said partition, said partition being adapted to prevent the cooling of said luminous tube by the air current produced during the rotation of said scanning disc.
